ANIMAL BED

Christian Dvore, Box 104, McHenry, Ill. 60050

Filed Nov. 2, 1966, Ser. No. 4,510

Term of patent 14 years

(Cl. D30—41)

The dominant features of my design reside in the portions shown by means of full lines in the drawing, with the upright wall forming portions thereof having an appearance which is characteristic of fiberglass sheet material.

I claim:

The ornamental design for an animal bed, substantially as shown and described.
